NURSERY TRAY

Ted L. Paxton, P.O. Box 2006, Magnolia Center Station,
Riverside, Calif. 92506

Filed Jan. 29, 1968, Ser. No. 10,351

Term of patent 14 years

(Cl. D35—3)

FIG. 1.

FIG. 2.

FIG. 3.

FIGURE 1 is a top plan view of a nursery tray showing my new design.

FIGURE 2 is a side elevational view thereof.

FIGURE 3 is an end elevational view thereof.

The side and end opposite those shown in FIGURES 2 and 3 are identical respectively thereto, while the downward facing surface of the bottom is merely the converse of the upwardly disposed visible surface thereof shown in FIGURE 1.

I claim:

The ornamental design for a nursery tray, as shown and described.
